UNITED STATES PATENT OFFICE

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN

CALCULATING MACHINE

Application filed December 3, 1923. Serial No. 678,140.

This invention relates to calculating machines, and more particularly to the type adapted expeditiously to perform calculations involving multiplication and division, 5 as well as perform the simpler computations of addition and subtraction:

Objects of my invention, among others, are to equip calculating machines with an improved and simple attachment or equipment 10 adapted to cooperate with the mechanism of the calculating machine to perform computations of multiplication and division and constructed to permit the calculating machine to be used independently to perform its ordinary operation of addition and subtraction, 15 the attachment being applied without necessitating any change in the calculating machine, which may be already in use; to embody in the multiplying and dividing attachment novel and improved driving and control mechanisms for differentially propelling the actuators for the accumulator; to provide improved detent mechanism for restraining actuation of the driving arms for 20 the accumulator actuating devices of lower denominations, when the same are not to be controlled during dividing and multiplying operations by the amount determining control means of the multiplying and dividing 25 attachment set to represent the divisor of a division problem or the multiplicand of a multiplication problem; to provide improved means for conditioning the machine for multiplication or division; and to equip the 30 machine with a counter actuated through novel means to display the quotient, when the machine is used to perform division, or the multiplicand when the machine is used to perform multiplication.

With the above and incidental objects in view, the invention consists in certain novel features of construction and combination of parts, the essential elements whereof are recited in the appended claims and the preferred form of embodiment of which is described in detail hereinafter and illustrated in full in the accompanying drawings which form part of this specification.

Of said drawings, Fig. 1 is a perspective view of a machine embodying my invention,

the machine being shown set for multiplication, with the auxiliary control carriage in its second or tens columnar position and with the parts shown in normal or home condition; Fig. 2 is a perspective view of the control or indexing stop unit for the first or units order represented on the auxiliary control carriage; Fig. 3 is a perspective view of one of the indexing stop units representing the tens and higher denominations; Fig. 4 is a right-hand side elevation showing the machine in normal condition with the casing of the calculator removed; Fig. 5 is a horizontal, section- 55 alized, plan view, as viewed from the rear, of a somewhat diagrammatic nature, showing the indexing stop units and fixed stop arms on the auxiliary control carriage and parts 60 cooperating therewith, the section being taken substantially on the line 5—5 of Figs. 4 and 7 and with the control carriage in its second or tens ordinal position; Fig. 6 is an enlarged section view on the line 6—6 of Fig. 9, showing 65 one of the counter wheels and its spring pressed turn-to-zero pawl in engagement with the turn-to-zero notch in the supporting 70 shaft; Fig. 7 is a vertical longitudinal section through the machine taken just within the right-hand side frame and exposing to 75 view the various mechanisms appropriate to the units order; Fig. 8 is a longitudinal section through the counting mechanism on the line 8—8 of Figs. 4 and 7, showing the normal relation of the turn-to-zero pawls on the 80 wheels to the notches in the supporting shaft; Fig. 9 is a similar section, through part of the 85 counting mechanism, but is foreshortened and shows the supporting shaft shifted to its turn-to-zero position so that its notches will engage the turn-to-zero pawls and restore the 90 counting wheels to zero when the shaft is rotated; Fig. 10 is a fragmentary sectional detail showing one of the restraining latches in latching relation with its appropriate 95 spring-pressed driving arm; Fig. 11 is a right side elevation of the multiplying and dividing attachment with some parts in section and others broken away, showing the parts in the position which they assume when the operating crank has been given one-half of its stroke during a multiplying operation 100.

with the first or units indexing stop unit in its "3" position and the auxiliary control carriage in its first or units columnar position; Fig. 12 is a skeletonized sectional view, taken just within the right hand frame plate of the multiplying attachment, and shows the positions which the parts assume when the operating crank has been given one-half of its stroke during a dividing operation, with the units indexing stop unit in its "3" position and the auxiliary control carriage in its first or units columnar positions; Fig. 13 is a detail side view of certain of the parts disclosed in Fig. 11, showing them in the positions which they assume when the manually operated control frame has been rocked to permit operation of the depressible keys of the calculator and lock the operating crank against actuation, hence disabling the multiplying and dividing attachment; Fig. 14 is a vertical transverse sectional view, showing the counting mechanism and the auxiliary control carriage in rear elevation, the section being taken substantially on the line 14—14 of Fig. 4; Fig. 15 is an enlarged fragmentary rear view of the lower parts of the quotient and multiplier pawls and their carrying arm of one order and the upper end of the operating lever with its roller in disabling alignment with the quotient pawl; Fig. 16 is a detail perspective view, looking from the rear, of the rock cradle or frame and associated pawl for disabling the multiplying and dividing attachment and permitting operation of the depressible keys, when in one position, and for enabling the attachment, when in its other position; Fig. 17 is a horizontal sectional view through the multiplying and dividing attachment, the section being taken in slightly different planes but substantially on the line 17—17 of Figs. 11 and 14, with the manually set indicating wheels on the control carriage shown in plan elevation and the machine set for multiplication with the parts in normal condition; Fig. 18 is an unwrapped or developed view of one of the counting wheels to show the series of quotient and multiplier digits; Fig. 19 is a horizontal section on the line 19—19 of Fig. 11, illustrating the shiftable sight slide in adding (multiplying) position to enable reading of the multiplier displayed on the counting wheels; Fig. 20 is an enlarged fragmentary sectional view taken through the accumulating section at the front end of the machine; Fig. 21 is a fragmentary front view of the left-hand portion of the control carriage, showing the manual set lever, for conditioning the machine for multiplication and division, in subtraction (division) position; Fig. 22 is a detail enlarged section taken on the line 22—22 of Fig. 14, the section being taken through the control lever and associated parts; and Fig. 23 is a detail section on the line 23—23 of Fig. 4, showing the connections between

the operating crank and the connecting link extending to the main operating cam.

As already stated, my invention contemplates the use of the multiplying and dividing mechanism or attachment in connection with a commercial form of calculating machine now on the market, the combination being effected in such a manner that the calculating machine may be used in its ordinary way, without change, and independently of the multiplying and dividing attachment, to perform the simpler operations of addition and subtraction. While I have shown my invention applied to the well-known commercial form of Burroughs calculator, it is to be understood that it is susceptible of use with other kinds of calculators and may, if desired, be incorporated in the machine as an integral mechanism thereof. The Burroughs calculator is a key-driven machine comprising, in general, an accumulator, consisting of a plurality of denominational numeral wheels, differential actuating devices, one for each accumulator wheel, and a multiple order key-board including banks of keys, one bank for each actuating device. This calculator, with my invention applied, may be used with accuracy, expediency and rapidity to perform operations of addition and subtraction, as is well understood in the art, and may also be used, but without the same facility or certainty, to perform computations involving multiplication and division. For the purpose of performing the more intricate computations of multiplication and division with certainty, dispatch, and but little experience or training on the part of the operator, I have equipped the calculator with an attachment comprising, in general, an ordinarily shiftable auxiliary control carriage, carrying manually set control or indexing stop units; an operating crank; driving arms driven through springs by the crank for propelling the differential actuating devices for the accumulating wheels under the control of the indexing stop units which are adapted to be set by finger pieces to represent one of the factors of a multiplying or dividing problem and each of which comprises complementary arranged stepped plates; means for shifting the auxiliary control carriage from order to order relative to the accumulator actuating devices; a lever and connections on the carriage for shifting the control units to selectively position their stepped plates into operative or effective alignment with the driving arms so that the accumulator actuating devices are moved extents proportional to the value represented by the setting of the control units during a multiplying operation and complementary extents during a dividing operation and mechanism comprising counting wheels and actuating devices for displaying the multiplier of a multiplication problem and the quotient of a division problem. For

the sake of convenience, this attachment will be referred to as the multiplying attachment or section, although it is understood that it is also used in performing the process of division and other computations.

Burroughs calculator

The well-known form of Burroughs calculator, to which I have applied my invention, is fully illustrated and described in the Horton Patent No. 1,326,504, with some slight modifications, as will be pointed out presently; and in order to identify some of the parts shown in the present drawings more readily, I will utilize the same reference characters as employed for similar parts in the Horton patent.

Referring now to Figs. 1 and 20 of the present drawings, the accumulator comprises the numeral wheels A and the associated gear wheels A' which carry the planetary pinions D meshing with sun gears E and with internal gears F on the numeral wheels. The carrying mechanisms comprise cams G and sun gears P carried by the numeral wheels, intermediate internal gear wheels C on the hubs of the sun gears E, oscillating gear carriers L, whose gears N and O mesh respectively, with the internal gears C and the sun gears E, and levers H having teeth on their upper ends in mesh with the teeth on the carriers L and held with their studs H² against the cams G by springs J, all as substantially shown and described in the aforementioned Horton patent. Gear wheels E² mesh with gear wheels A' and the gear wheels E² are provided with circular flanges E³ provided with internal teeth and engaged by spring-pressed ratchet pawls 9, pivoted on pinions 8 meshing with oscillating segments E' which derive power from the depressible calculator keys 27 through connections comprising stop bars E³⁰ (Fig. 7) coupled to the segments, bell-crank levers B to which the rear ends of the stop bars are pivoted and key-driven levers F' connected at their forward ends by links F² to the stop bars E³⁰. It will be understood that through these driving connections and restoring springs 28, connected to the levers B, depression of key 27 causes oscillation of the segments E' and that through the medium of the gear wheels E², the aforesaid ratchet and pawl connections and the planetary gearing, the numeral wheels A are advanced in a clockwise direction, as viewed from the right-hand side of the machine, extents proportionate to the value of the depressed keys. The corresponding rotation of the cams G swings the upper ends of the levers H forward and when the high points of the cam pass the lever studs H², the levers H are operated to transmit carrying impulses, as fully explained in the above-mentioned Horton patent.

As in the Horton patent, zeroizing or

clearing of the numeral wheels A is accomplished by oscillating the gear carriers L in opposition to the springs J, the intermediate gears C being locked against rotation in a clockwise direction by engagement of the upper hooked ends of arms 2 with studs e on gear disc C, so that the numeral wheels A will be turned to zero by the turning of the gears N, O and P. The locking levers 2 are operated to lock the gears C through the bail 5, the cross-rod 6 of which extends through slots in the lower ends of the levers. The bail is fast on a shaft S, which is oscillated by a crank handle W (Fig. 1) through suitable connections, not illustrated in the present drawings but fully shown and described in the aforesaid Horton patent. The downward movement of the rod 6, as caused by the pulling forward of the crank handle W, besides operating the levers 2 also serves to drive the levers H by engaging their lower projections H³, to supplement the action of the springs J and insure the zeroizing action of said levers H even though the springs should fail to operate.

For the purpose of preventing backward rotation of the gears E², upon forward actuation of the segments E', I employ yoke-shaped back-stop pawls z provided with noses Z' adapted to engage the under-cut teeth of ratchet wheels Y fast on the same hubs with the corresponding gear wheels E², the pawls being retained in engagement with the ratchet wheels through springs R³. This construction is slightly different from that shown in the Horton patent, in which the corresponding pawls engage laterally projecting teeth on the gear wheels E² and with which pawls 9 on the gears 8 coact to drive the gear wheels E², said circular flanges E³ (Fig. 20) with the internal ratchet teeth being employed in my construction in place of the offset teeth E³ on the gears E² of the Horton construction. A cross-shaft 10 is provided with arms 11 having projections 11² which, when the shaft is rocked during a zeroizing operation, engage projections Z² on the pawls Z rocking the pawls to release them from engagement with the undercut teeth of the corresponding ratchets Y. The arms 11 also have noses 11^a which, when the shaft 10 is rocked, engage the upper extensions of the driving pawls 9 (which extend toward the right beyond the flanges E³ to permit this engagement), thus rocking the pawls 9 to release them from engagement with the internal ratchet teeth, the ratchet and pawl connections being disabled to avoid any interference with the reverse rotation of the gear wheels E² which accompanies a backward turning of the numeral wheels during a zeroizing operation. The shaft 10 is operated through connections with the aforesaid rock shaft S, which comprise an arm 31 having a stud 12 engaging in a slot 130

in a cam plate 13, which at its upper end has one end forked to engage a stud on an arm 10^b fast on the shaft 10, all as described in the Horton patent.

5 *Frame of multiplying attachment*

J-shaped side plates 32 and 33 (Figs. 4 and 7) are fastened by pairs of screws 34 to the rear ends of the opposite side frames of the calculator and these side plates have notches 35 in their lower edges which engage over a cross-rod 36 and act as supporting guides to assist in properly positioning the multiplying section on the rear end of the calculator. The upper ends of the forward vertical arms of the side plates 32 and 33 are provided with inwardly extending ears 30 (Figs. 17 and 21) rigidly connected to and supporting a cross-bar 37 which is formed to constitute a track for the ordinarily shiftable auxiliary control carriage, to be described later, and the vertical rear arms of the plates are connected near their upper ends by means of cross-rods 38, 39 and 40, the intermediate portions of the plates being also connected together by other cross-rods and shafts, as will be pointed out later.

30 *Operating mechanism and differential driving connections of the multiplying attachment*

Pivottally connected near the upper end of each of the bell-crank levers B is an irregularly shaped connecting link or arm 42 (Figs. 7 and 12) having a bayonet-shaped slot 43 in its rear end through which projects a flanged supporting stud 44, projecting laterally from a spring-operated driving arm 45, it being understood that there is one of these links 42 and a corresponding driving arm 45 for each denomination represented in the calculator. The driving arms 45 are suitably spaced and loosely mounted on a cross-rod 46, supported at its ends in the side plates 32 and 33. On the same shaft 46 and suitably spaced from the driving arms 45 are vertical extending arms 47 having rearward extensions connected to the upper ends of springs 48, the lower ends of which are connected to rearwardly and downwardly extending projections on the driving arms 45. Each of the arms 47 carries a roller 49 which rides on the periphery of an appropriate cam-shaped plate 50 and the plates 50, there being one for each arm 47, are fast to a rock shaft 51 journaled at its ends in the side plates 32 and 33.

Fast on the right-hand projecting end of the shaft 51 (Figs. 1 and 4) is a goose-neck cam plate 52 having pivoted thereto by a shoulder screw and nut 59 the rear end of a link 53 connected at its forward end to a crank arm 54 fast to the inner end of a stub shaft 55, which has keyed on its outer end an operating crank 56, held in place on the shaft 55 by a suitable washer and nut. The shaft 55 is

suitably journaled in the upper end of the bracket 57 which is fastened to the under side of a base-plate 58 which supports the machine.

From the above description, it will be evident that, upon each complete rotation of the crank handle 56 (in a clockwise direction, as viewed from the right side of the machine), the crank 54 and link 53 impart a reciprocating movement to the cam plate 52, acting as a crank arm, and the shaft 51 through an arc of approximately 90 degrees, first in a clockwise and then in a counterclockwise direction and that the cams 50, fast on the shaft 51, through their coaction with the rollers 49, rock the arms 47 forwardly in variable extents and then permit the springs 48 to rock the arms rearwardly to normal position. When the arms 47 are rocked forwardly in this manner, the springs 48, serving as yielding connections between the arms 47 and the driving arms 45, rock the arms 45 forwardly until they are arrested in different positions determined by the setting of the indexing stop units to be described later. As the studs 44 on the arms 45 are seated in the forward ends of the slots 43, the links 42, levers B, stop bars E³⁰ and segments E' are moved forwardly proper extents to actuate the accumulating wheels and add or subtract the number represented by the settings of the control units on the accumulator. The springs 48 are stronger than the restoring springs 28 connected to the levers B. Upon return rearward movement of the arms 47, their lips 60 which extend laterally from their forward edges in front of the arms 45 engage the latter and restore them to normal position, the arms 45 being arrested in normal position by their engagement with the shaft 51.

In order to automatically assist the operator in operating the machine during the first half of the stroke of the crank handle 56, at which time the greatest load is on the handle and to also provide a slight resistance to the return of the crank handle 56 during the last half of its stroke, at which time the load of the operating parts has been removed from the handle and thus provide for a smooth and easy operation of the machine throughout the entire stroke of the crank handle, a crank arm 63 (Figs. 4 and 17) is fastened to the left-hand end of the shaft 51 and is provided at its outer end with a stud to which one end of a spring 65 is connected, the other end of the spring being connected to a stud on the left side plate 33. The spring 65 is normally under tension, as shown in Fig. 4, but not sufficiently to operate the machine, and during the first half of the stroke of the crank handle 56, rotation of the shaft 51 in a clockwise direction releases the tension of the spring 65 which has assisted the operator in actuating the parts, but during the second

half of the stroke of the handle, when the shaft 51 is rocked counter-clockwise, the spring 65 is again placed under tension, thereby providing a slight resistance to the return 5 of the handle.

For the purpose of accurately positioning the above-described operating mechanism in its normal position, there is provided a spring-operated return arm 66 (Fig. 4) supported at its lower end on a shoulder screw 67, threaded into the right-hand side plate 32. The upper end of the arm is provided with a stud to which is connected the forward end of a spring 68 connected at its rear end 10 to stud on the side plate 32, the spring normally acting to retain the arm 66 in the normal position shown in Fig. 4, with its roller stud 69 thereon, seated in the upper end of a recess 70 of the cam plates 52. When the 15 cam 52 moves clockwise the roller 69 rides on the edge of the cam and stretches the spring 68. As the cam returns toward its home position shown in Fig. 4, the roller 69 moves into the slot 70 which is shaped so that the pressure of the roller under the tension of spring 20 68 tends to cause the cam to occupy its home position. If the cam should be moved slightly past its home position, the roller returns it. If it is stopped slightly short of its home 25 position, the roller acting on the edge of the cam moves the latter to final position.

A pawl 71, pivoted on the bracket 57 (Figs. 4 and 23) cooperates with a ratchet 72, which is mounted on the shaft 55 and fastened to 30 the crank arm 54 by means of a rivet. The pawl 71 is connected to a spring 73 and cooperates with the ratchet to prevent return movement of the operating crank 56 in a counter-clockwise direction, once it has been 35 moved clockwise in its normal direction of movement from its normal position. Several teeth have been omitted from the ratchet on its lower side, thereby forming a smooth surface against which the pawl 71 bears when 40 the handle is in normal position, the object of this smooth surface being to allow a small amount of play to the handle to take care of any slight overthrow of it due to momentum, before the pawl engages the ratchet teeth.

50 *Indexing stop units and indicating wheels*

In general, the means for controlling the differential extents of movement of the spring-operated driving arms 45, and hence 55 of the corresponding accumulator wheels, when the machine is used to perform division or multiplication, as the case may be, comprises a plurality of control or indexing stop units manually positioned by means of finger-pieces adjustable on a laterally shiftable control carriage, adapted to be moved from one ordinal position to another, each control unit consisting of a pair of complementally stepped plates, one plate of each unit being 60 employed in multiplying operations to limit 65

the forward movements of the spring-pressed driving arms 45 so that the corresponding accumulating wheels are advanced a number of steps directly proportional to the value of the setting of the control units, while the other plate of each unit is employed in dividing operations to arrest movement of the driving arms 45 and hence of the corresponding accumulator wheels after the same have moved extents complementary to the value 70 represented by the setting of the control units, the units being shiftable laterally to position, the multiplying or dividing plates 75 in operative alignment with the driving arms 45, when the machine is conditioned for multiplication or division, as the case may be 80 and as will be described later.

From what has been stated above, it is evident that the process of division is carried out with my machine by repeated subtraction of the divisor from the dividend, set up on the accumulator, and that this subtractive operation is performed by adding the complement of the divisor to the dividend (and successive remainders thereof), 9's being automatically added during each stroke of the operating crank 56 in a dividing operation on all of the accumulator wheels of higher denominations than that actuated under the control of the subtracting plate 82 set to 90 represent the digit of highest denomination represented in the divisor.

The control carriage comprises a suitably grooved slideway 75, mounted to slide laterally on the rail or track 37, and a plate 76, 100 carrying the control units and mounted on the slideway 75 to move therewith, as will be described later. In order to aid in supporting and guiding the plate 76 in its sliding movement, it is provided near its upper 105 end with brackets or plates 74 (Figs. 7 and 8) through holes in which the guide rod 38 extends.

As best shown in Figs. 1 and 14, the carriage plate 76 is provided with six vertical slots 77 through which extend finger-pieces 78, projecting forwardly from the upper ends of the control or indexing stop units 79, (Figs. 2, 3, 14 and 17). Each of these indexing stop units comprises a slide 80, a stepped indexing plate 81, called the "adding" plate herein, a parallel plate 82, complementally stepped with relation to the companion adding plate and called the "subtracting" plate herein, and a rack 83 secured to the side of the adding 110 plate 81 by studs 81^a, the adding plate preferably being integral with the slide 80 and the subtracting plate being connected to the slide in any suitable manner. The slide-plates 80 are provided with slots 84 in their lower portions and shouldered studs 85 project from the carriage plate 76 through the slots, the indexing stop units being thereby guided for sliding vertical movement on the carriage plate 76 by the movement of the rear reduced 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

ends of the finger pieces 78 in the slots 77 and the studs 85 in the slots 84. The finger pieces are gripped by the operator to move the indexing stop units to the desired positions to represent the divisor or the multiplicand, as the case may be.

The carriage plate 76 is also provided with six apertures 87 (Fig. 1) through which slightly extend the peripheries of number wheels 88 having fast thereon pinions 89 (Figs. 11 and 12) meshing with the corresponding racks 83 on the indexing stop units. The number wheels 88 with their pinions 89 are loose upon studs projecting laterally from brackets 86 (Figs. 11, 14 and 17) secured to the rear side of the carriage plate 76 and between the indexing stop units by laterally projecting lugs or ears. The indicating wheels 88 are in alignment with the banks 20 of keys 27, and hence with the eight openings A^2 through which the accumulator wheels A display their numbers, and it will be evident that when the finger-pieces 78 are moved to position the indexing stop units to 25 represent the value of the multiplicand in a multiplying operation or the divisor in a dividing operation, the indicating wheels 88 are accordingly positioned to display to the operator the multiplicand or the divisor, as 30 the case may be and thus assist him in properly setting the indexing stop units.

Bell-crank detent pawls 91 are pivoted at 92 on the brackets 86 and the noses on the upper ends of their vertical arms engage the 35 pinions 89 while lugs on the forward ends of their horizontal arms are connected to one end of springs 96 connected at their opposite end to studs on the brackets 86, the springs being of sufficient strength to cause 40 the pawls to properly align the numeral wheels 88 and maintain the indexing stop units in their different positions of adjustment.

From what has been said, it will be understood that the auxiliary control carriage may be shifted laterally from one order to another, in a manner to be described later, to bring the indicating wheels 88 into alignment with the banks of keys 27 of the proper 50 denomination dependent upon the number of denominations or places represented in the multiplicand or to be represented in the quotient, but for the present it might be assumed that the carriage is in its extreme 55 right-hand position with the unit or right-hand number wheel 88 in alignment with the units bank of keys 27 of the calculator. It might also be well to state here that the carriage plate 76 is mounted on the slideway 75 and connected thereto in such a manner that it may be given a slight shifting movement relative to the slideway, while the slideway is in stationary position, for the purpose of 60 moving the adding plates 81 into operative alignment with the spring-operated driving 65

arm 45, when the machine is conditioned for performing multiplication or to bring the subtracting plates 82 into such operative alignment when the machine is conditioned for performing division. Before describing 70 the mechanism for ordinarily shifting the auxiliary control carriage, or the mechanism for conditioning the machine for multiplication or division, it will be well to describe first the specific construction of the adding 75 and subtracting plates 81 and 82 and the operation of the accumulator actuating devices under their control.

The adding plates 81 for all of the indexing stop units are all alike and similarly positioned on the respective slides 80. For the sake of illustration, I have applied the naughts and digits to the stops of the adding plates shown in Figs. 2 and 3, the digits of the respective stops being representative of the number of steps of movement which the spring-operated driving arms 45 are given when arrested by the respective stops during forward oscillation of the driving arms 45 to move the actuating devices of the accumulator differentially. For example and assuming that the machine is conditioned for performing multiplication, if the units control unit is moved to its "3" position, shown in Fig. 11, in which position "3" is displayed 90 by the corresponding units numeral wheel 88, the "3" stop is moved into the path of movement of a lug or ear 97 extending laterally from the thickened upper end of the spring pressed driving arm 45 of units denomination, assuming that the control carriage is in units or first position, so that when the arm 45 is swung forwardly, as above described, this "3" stop is engaged by the lug 97, as shown in Fig. 11, and hence arrests 100 the movement of the units driving arm 45 after the same has been swung forwardly three steps of movement. In Fig. 11 the parts are shown in the positions which they assume when the operating crank 56 has been 105 given one-half of its stroke of operation.

As above stated, the process of division is performed by successive additions of the complement of the divisor to the dividend (and to the successive remainders thereof) set up, 115 on the accumulator. It is understood that "0's" to the right of the digit of lowest order in the divisor are ignored or disregarded when the divisor is set upon the auxiliary control carriage. For example, the divisor 120 50 (or 500) is set up as "5" by moving the units control unit to its "5" position, as many places being pointed off or eliminated in the quotient as there are ciphers to the right of the digit of lowest order in the divisor, as 125 will be more fully pointed out later. As division is accomplished by adding the complement of the divisor, an extra "1" is added under the control of the units subtraction plate 82, and therefore this subtracting plate 130

is complementally arranged relative to the companion units adding plate 81, with respect to "10", while the subtracting plates 82 for the control units of higher denominations 5 are complementally arranged with respect to their companion adding plates 81 with respect to "9", as will be best understood by referring to Figs. 2 and 3, in which I have also applied digits to the stop of the subtracting plates. Assume, now, that the machine is conditioned for performing division, in which case the subtraction plates 82 are in the zones of movement or operative alignment with the lugs 97 on the arms 45, and the units 10 control unit is moved to its "3" position, as before, if it is not already in such position, the units driving arm 45 (assuming that the control carriage is in its units or first position) is moved forwardly seven steps to the 15 position shown in Fig. 12, at the end of which movement it is arrested by engagement of the lug 97 with the "7" stop on the subtracting plate, thereby causing the units accumulator wheel A to be advanced seven steps to add thereon "7" which is the complement of "3" with respect to "10". If at the same time one of the control units of higher order is moved to its "3" position by its finger-piece 20 78, the driving arm 45 in alignment therewith moves forwardly six steps, to advance the corresponding accumulator wheel A a like number of steps to add thereon "6"—the complement of "3" with respect to "9". If a "0" occurs in the divisor in an order 25 higher than the lowest denomination represented by a digit, the corresponding indexing stop unit is allowed to remain in "0" position, and upon operation of the machine the driving arm 45 and hence the corresponding actuating segment E' are moved forward nine steps to add "9" on the corresponding 30 accumulator wheel, and all of the driving arms 45 and corresponding actuating segments E' of higher orders than the arm and segment of highest order actuated under control of the control stop unit set to represent the digit of highest order in the divisor, are actuated nine steps, the actuating cams 47 being so constructed that the driving arms 47 and hence the unrestrained spring-operated 35 driving arms 45 are rocked nine steps of movement upon each rotation of the operating crank 56.

When the machine is conditioned for performing multiplication, the driving arms 45 of higher order than the one controlled by the control unit positioned to represent the digit of highest order in the multiplicand must be restrained from movement, and to this end the "0" stops on the control units which are allowed to remain in zero position prevent operation of the arms 45 in alignment therewith and four arms 100, (Figs. 5, 14 and 17) secured to the carriage plate 76 and having their rear ends in the same horizontal plane

as the "0" stops on the adding plates, when the latter are in normal "0" position, coat with the upper ends of the driving arms 45 of higher denominations, being in operative alignment therewith as shown in Fig. 17, to prevent their operation during multiplying operations. When the machine is conditioned for division, the arms 100, as shown in Fig. 5, are out of alignment with the driving arms 45 of higher orders so that these arms 75 are permitted to move forwardly nine steps for the purpose above explained.

Latching means for driving arms 45 of lower orders

When the machine is used to perform multiplication, the control carriage is shifted from order to order from right to left, depending upon the number of places or denominations represented in the multiplier, the operating crank 56 being given a number of strokes, with the carriage in each ordinal position, dependent upon the value of the digit in the corresponding denomination of the multiplier. For example, if the multiplier is "32", the crank is given two rotations with the control carriage in its units or extreme right-hand position as the digit "2" appears in the units order, and then the carriage is moved one order or place towards the left and the crank is given three rotations, the digit "3" appearing in the tens order of the multiplier. When the machine is used to perform a problem in division, the carriage is shifted in the reverse direction, that is from left to right and in each ordinal position the crank is given a number of rotations dependent upon the number of times the divisor is contained in the dividend or in the portion of the dividend (or remainder) displayed by the accumulator wheels A in alignment with and to the right of the divisor displayed on the wheels 88. It will be obvious therefore, that it is necessary to prevent operation of the actuating mechanisms for the accumulator wheels A of denominations lower than the denomination represented by the ordinal position of the control carriage. For example, if the carriage is in its extreme left-hand or sixth position, the five actuating arms 45 of lower denominations are not under the control of the indexing stop units and it is then necessary to block these five arms against actuation. To this end the following means are employed:

Five latches 101 (Figs. 5, 7, 10 and 17) are loosely mounted and suitably spaced by spacing collars on a cross-rod 102 supported at its ends by the side plates 32 and 33. There are only five of these latches and they are in operative alignment with the five right-hand spring-operated driving arms 45, because in the particular machine disclosed in the drawings, the carriage has only a range of six positions and when in its sixth position, which is the last one to the left, a registra-

tion takes place on the sixth accumulator wheel aligned with the digit in the units order of the multiplicand or divisor and represented by the position of the units indexing stop unit, so that the driving arm 45 for that particular order must be capable of movement to effect registration, while in the five lower orders to the right, the driving arms 45 must be capable of being locked against movement. The forward ends of the latches 101 are provided with noses 103 adapted to engage and ride on the upper edge of a U-shaped bail 104 whose side arms are riveted or otherwise fastened to the rear side of the carriage plate 76. When the carriage is in its extreme right-hand position, which is its units or first position, shown in Figs. 14 and 17, hooks or noses 105 (Fig. 7) projecting downwardly from the forward end of the latches are, in elevated position out of engagement with laterally projecting lugs 106 on the five arms 45 of lower denominations, the lugs 106 being parallel to and to the rear of the above-mentioned lugs 97, the latches being retained in this position by the engagement of their noses 103 with the top edge of the bridge of the bail 104, so that actuation of these arms 45 is permitted under the control of the indexing stop units. When the carriage is moved one step toward the left, (as viewed from the front) to its tens or second position as shown in Fig. 5, the bridge of the bail 104 moves beyond the zone of the units or right-hand latch 101, thus permitting its spring 107 to rock it counterclockwise to move its nose 105 in front of the lug 106 on the units arm 45, thus blocking that arm against operation. As the carriage is stepped further toward the left, the same procedure of locking the driving arms 45 takes place in the successive orders, until when the carriage has been moved to its last or sixth position, the five latches 101 are all released and lock their respective driving arms 45 against forward actuation. In a dividing operation, this condition is reversed as the carriage moves from the left to the right. With the carriage in its sixth position, the five driving arms 45 of lower denominations are blocked against operation, as it is not intended that registration should take place in these denominations. As the carriage is moved toward the right one step to its fifth position, the inclined end (the right as viewed from the front and the left as viewed in Fig. 14) of the top edge of the bridge of the bail 104 engages under the nose 103 on the fifth or last pawl 101 to the left, as viewed from the front of the machine, thereby raising it to permit actuation of the corresponding driving arm 45 upon operation of the operating crank, with the carriage in its fifth position. As the control carriage is moved still further to the right, the bail 104 picks up the successive latches 101, thereby releasing their re-

spective driving arms 45, as the bail is brought within the zones of the latches.

The latches 101 have upwardly and forwardly curved tails whose forward ends engage a cross-rod 109 when the latches are in effective latching positions, the rod serving to limit the movement of the latches to latching position.

Means for ordinarily shifting the control carriage.

75

The lower edge of the grooved slideway 75 is formed to provide a rack 110 (Fig. 14), extending about two-thirds of its length, and of sufficient length to permit shifting of the control carriage from one extreme position to the other. In mesh with this rack 110 at the left-hand side of the machine, as viewed from the front, is a gear 111 fast on a shaft 112 extending longitudinally of the machine adjacent the left side thereof and at right angles to the slideway 75, the shaft being supported near its rear end in a bracket 113, (fastened to the left-hand frame 33 in any suitable manner) and supported near its forward end in a bracket 114 (Figs. 1 and 7) secured to the base 58. Secured to the forward end of the shaft 112 is a hand wheel 115 for rotating the shaft and pinion 111 and as the latter meshes with the rack 110 the control carriage is shifted toward the left or the right, as the case may be, on the track or rail 37.

Fast on the shaft 112 near its rear end, as best shown in Figs. 14, 17 and 21, is a star wheel 116 with which coacts a roller stud 117 projecting from an arm 118 pivoted by a stud 119 to the track or rail 37. A strong spring 120 is connected at its upper end to a stud on the arm 118 and at its lower end to a hole in the bracket 113 and firmly holds the roller stud 117 in engagement with the star wheel 116 to accurately align the carriage in its selected columnar position and prevent its accidental displacement from such position.

Means for conditioning machine for addition (multiplication) or subtraction (division)

100

As above stated, when the machine is to be changed from multiplying condition to dividing condition, or vice versa, the carriage plate 76 is moved slightly relative to the slideway 75 to move the adding plates 81 into operative alignment with the driving arms 45, if a problem in multiplication is to be performed, or to shift the subtracting plates 82 into such operative alignment, if a problem in division is to be performed. The mechanism for so shifting the plate 76 will now be described.

The carriage plate 76 is supported on the slideway 75 by shouldered screws 121, which, as best shown in Figs. 14 and 21, extend from the slideway through horizontal elongated limiting slots 122 in the plate 76, the studs being threaded into the slideway. A lower

123 (Figs. 1, 14, 21 and 22) is pivoted by a screw 134 to the front side and near the left-hand end of the carriage plate 76 and its upper end is forked to accommodate a stud 125 projecting rearwardly from a finger-piece 126. The shouldered stud 125, which extends through an arcuate slot 127 in the carriage plate 76, is secured at its rear end to the upper end of a lever 128 which carries a stud 141 projecting through a vertical slot 142 in the carriage plate 76, and the lever is pivoted on a headed stud 124, threaded into the slideway 75. The slot 142 is of the same width as the diameter of the roller stud 141 but slightly greater in its vertical dimension, thereby allowing a slight vertical movement of the stud 141 in the slot 142 without binding when the levers 123 and 128 are shifted by the finger-piece 126 from their adding position (shown in Fig. 1) to their subtracting position (shown in Fig. 21), or vice versa, the angular movement of the lever 128 being such as to cause this slight vertical movement of the stud 141 in the slot 142. Now, as the spring-pressed roller 117 exerts sufficient pressure on the star wheel 116 to prevent turning of the gear 111, in mesh with the rack 110 on the slideway 75, unless the operating wheel 115 is rotated, and, as the stud 124 is fast in the slideway 75, this stud becomes the fulcrum about which the lever 128 turns when moved from one position to another and the stud 141 acts on one side or the other of the slot 142 and shifts the carriage plate 76 relative to the slideway 75, the plate being shifted toward the right, as viewed in Fig. 14, when the lever is moved from the adding position, shown in Figs. 1 and 14, to the subtracting position shown in Fig. 21, thereby shifting the subtracting plates 82 into operative alignment with the spring-operated driving arms 45 as shown in Fig. 5. Conversely when the lever 128 is moved by the finger piece 126 from its subtracting position to its adding position, the carriage plate 76 with its associated parts will be shifted to the right (as viewed in Fig. 1) thereby moving the adding plate 81 and the stop arms 100 into operative alignment with the driving arms 45 as shown in Figs. 14 and 17. The stud 124 projects through a horizontal slot 144 formed in the plate 76 to accommodate the movement of the plate.

For the purpose of retaining the carriage plate 76 in its adding or subtracting position on the slideway 75, the lower end of the lever 128 is provided with a plate 132 (Figs. 14, 21 and 22) slidably mounted for vertical movement thereon by means of studs 135 on the lever 128 projecting through vertical slots 136 formed in the plate. The stud 124 also projects through a central vertical slot 137 in said plate. The plate 132 carries at its lower end a roller stud 130, extending into a positioning slot 131 in the slideway 75, a larger

slot 133 being formed in the carriage plate 76 to permit free movement of the roller stud therein and co-action of the stud in the slot 131. Both ends of the slot 131 form dwells with a rise on the upper edge of the slot between them, the ends of the slot being nearer the pivot pin 124 than is the rise. A spring 139, connected at its upper end to a stud on the lever 128 and at its lower end to a stud on the slide plate 132, forms a yielding connection between the lever and the slide plate so that when the lever 128 is moved from subtracting to adding position, or vice versa, the roller stud 130 on the lower end of the slide plate 132 passes over the rise between the two ends of the slot 131 and as the roller moves into one end of the slot, the spring 139 draws the slide plate upwardly and firmly seats the roller stud 130 into such end of the slot 131 and retains the same therein thereby firmly holding the carriage plate 76 in its set position on the slideway. The extent of movement of the carriage plate 76 on the slideway 75 in either direction is limited by the engagement of the shouldered supporting studs 121 with the extremities of the slots 122, through which the studs project.

Numerals wheels of counter mechanism and sight slide

We now come to the counter mechanism, the numeral wheels 147 (Figs. 1, 11 and 14) of which function to display the multiplier at the end of a multiplying computation or the quotient at the end of a division computation, the number wheels being cleared or restored to zero before each computation or calculation is begun. There are six of these numeral wheels 147, one for each ordinal position of the control carriage, these wheels being loosely mounted on a shaft 148, supported in suitable bearings in the side plates 32 and 33, as best shown in Figs. 8 and 9. The wheels are suitably spaced from each other by spacing collars between their hubs. As best seen in Figs. 14 and 18, the peripheries of the counting wheels have two sets of series of digits reading in opposite directions, with their "0's" in alignment, the left-hand shaded digits being used to indicate the quotient in a dividing operation and the unshaded numbers being used to indicate the multiplier in a multiplying operation.

The numerals on the reading line of the counting wheels, are displayed through sight openings 149 (Figs. 1 and 19) in a curved cover plate 150, positioned over the counting wheels and mounted by ears on the cross rods 38 and 40. The openings 149 are substantially the same width as the numeral wheels, but in order that only the quotient digits or the multiplier digits on the wheels may be viewed at a time, the cover 150 is provided with a slide plate 151 having openings 152 of substantially half the width of the numeral

wheels, so that only one set of numerals are visible at a time through the half-closed sight openings 149. The slide plate is slidably mounted at one end on a shouldered stud 153, 5 fast to the cover plate 150 and projecting through a slot in the plate 151, and at its opposite end by a shouldered finger-piece 154, the rear stud on the finger-piece projecting into a slot in the cover plate. The finger-piece 10 is employed to shift the slide plate 151 to adding or subtracting position, represented by the letters "A" and "S", respectively, in Fig. 1, so that when the slide plate is moved to the right, as shown in Fig. 1, only the digits representing the multiplier will be visible to the operator, while when the slide is shifted to the left to subtracting position, only the figures representing the quotient will be visible. It 15 is understood that when the machine is conditioned for addition or subtraction by shifting of the finger piece 126, the slide plate 151 should be similarly shifted.

Counter wheel actuating mechanism

25 Fastened on one end of the hub of each of the numeral wheels is a ratchet wheel 157 (Figs. 7, 8, 11 and 12) and on the enlarged portion of each hub is loosely mounted a pawl-carrying plate 158 having pivoted at 30 its lower end and to the right thereof, as viewed from the front of the machine, an operating pawl 160 called the "quotient" pawl herein, spaced from the pawl-carrying plate by a suitable spacing collar. On the opposite side of the lever or arm 158 is pivoted at 165 on operating pawl 159, designated herein as the "multiplier" pawl. Springs 161, connected at their forward ends to studs on their respective pawl-carrying arms 158 and 40 at their rear ends to the cross-rod 40, serve to normally retain the pawl-carrying arms in normal position, in which position, as shown in Fig. 7, they contact with the forward edge of a cross-plate 162 secured at its ends to the side plates 32 and 33. Springs 163, connecting forward extensions of the companion pawls 159 and 160, tend to rock the upper ends of the respective pawls into engagement with the ratchet wheels 157, but while 45 the arms 158 are in normal engagement with the forward edge of the cross-plate 162, the rear edges of the quotient pawls 160 likewise engage this edge, while the rear sides of downwardly extending arms 164 on the multiplier pawls also engage this edge and hence 55 the pawls are held out of engagement with the ratchet wheels against the influence of the springs 163.

In order to accurately align the numeral 60 wheels 147 in their set positions and prevent overthrow of the same, when actuated by the pawls 159 and 160, as will be described presently, there are provided six bell-crank levers 166, one for each ratchet wheel 157 and 65 mounted on the cross-rod 39. The forward

ends of the horizontal arms of the bell-crank levers 166 are provided with roller studs 169 engaging the notches of the ratchet wheels 157 to retain the number wheels in their set positions. The levers 166 are suitably spaced on the rod 39 by means of spacing collars or sleeves and spring 168, connected at their forward ends to the downwardly extending arms of the levers and at their rear ends to the cross-rod 40, act firmly to retain the roller studs 169 in contact with the ratchet wheels 157.

Upon each stroke of the operating crank 56, the pawl-carrying arm 158 appropriate to the counter wheel 147, corresponding to the ordinal position of the control carriage is oscillated, and either the pawl 159 or 160, dependent upon whether the machine is conditioned for multiplication or division by the finger piece 126, coacts with the corresponding ratchet wheel 157 (while the other pawl is disabled) to advance the counter wheel one step, that is to say, one step in a clockwise direction if the machine is conditioned for subtraction (division), or one step in the opposite direction if the machine is conditioned for addition (multiplication). This means for rocking the particular arm 158, corresponding to the ordinal position of the carriage, and rendering the multiplier or quotient pawl thereon ineffective, dependent upon whether the machine is conditioned for multiplication or division, will now be described.

A bell-crank lever 170 (Figs. 11, 12 and 14) is pivoted at 171 to an extension of the units number wheel supporting bracket 86 and carried at the upper end of the bell crank lever is a stud 167, which, when the machine is conditioned for multiplication, is positioned (as shown in Fig. 14) behind the quotient pawl 160 of the denomination corresponding to the ordinal position of the control carriage, and at the same time the stud and lever are to be left (as viewed from the rear) of the tail 164 of the companion multiplier pawl 159 to clear the same. When the machine is set for subtraction the stud 167 is positioned, as shown in Fig. 15, behind the tail 164 of the multiplier pawl 159, but is to the right (as viewed from the rear) of the companion quotient pawl 160. The lower end of the lever 170 carries a roller stud 172, which is positioned in vertical alignment with the cam plate 50 of the order corresponding to the columnar position of the control carriage, the roller being moved into alignment with the successive cams as the control carriage is shifted to the successive ordinal positions. A spring 173 connected at its rear end to a stud on the lever 170 and at its forward end to a stud on the bracket 86 for the units order, normally retains the operating lever 170 in the position

shown in Fig. 7 with the forward end of a forwardly extending projection 174 on the lever in engagement with rear face of the lug on the bracket 86 connecting the bracket to the carriage plate 76.

From the above description it will be evident, that, upon each operation of the operating crank 56, a projection 175 of the particular cam plate 50 in alignment with the 10 roller 172 on the lever 170 coacts with the roller, thereby rocking the lever 170 counter-clockwise an invariable extent, to the position shown in Figs. 11 and 12, the lever being restored to its normal position by its 15 spring 173 during the last half stroke of the operating crank. During the forward movement of the upper end of the lever 170, when the machine is conditioned for multiplication, its roller stud 167 contacts with 20 the rear edge of the pawl supporting arm 158 of the denomination corresponding to the columnar position of the carriage and rocks the arm and the pawls 159 and 160 to the position shown in Fig. 11. As the stud 167 is 25 out of alignment with the tail 164 of the pawl 159, the spring 163 rocks the pawl 159 about its pivot as the tail 164 moves out of engagement with the forward edge of the cross-plate 162, the pawl then riding freely 30 over the teeth of the ratchet wheel 157. During this forward movement, the companion quotient pawl 160 is held out of engagement with the ratchet wheel and into engagement with a limiting pin 180 on the arm 158 by 35 the stud 167 which also serves to hold this pawl in its disabled position during the return movement of the arm 158 by its spring 161. It will be evident that during this return movement, the multiplier pawl 159, being in engagement with one of the teeth of 40 the ratchet wheel 157, rotates the ratchet wheel and hence the number wheel, one step in a counter-clockwise direction to add "1" on the counter wheel whose multiplier digits, 45 brought to the reading line, are then viewed through the sight opening in the slide 151. With the machine conditioned for subtraction, the stud 167 when moved forwardly as before, engages the tail 164 of the multiplier 50 pawl 159, but clears the rear edge of the quotient pawl 160, so that the quotient pawl, when the arm 158 is rocked forwardly by the stud 137, rotates the corresponding ratchet 55 157 and the number wheel 147 in a clockwise direction to add "1" thereon, and upon return movement of the arm 158 the quotient pawl rides freely over the teeth of the ratchet while the multiplier pawl 159 is held out of 60 engagement with the ratchet teeth by the engagement of its tail 164 with the stud 167. During dividing operations the quotient digits on the number wheels are viewed through the sight openings in the slide 151 which has been moved to its subtracting (dividing) position.

Zeroizing of the counter wheels 147

At the end of each multiplying or dividing calculation, or before the machine is used to perform a new problem, the counter wheels 147 are turned to zero. For this purpose each of the counting wheels 147 has pivoted on its inner side a pawl 178 (Figs. 6, 8 and 9) having a nose 179 projecting through a cutaway portion in the hub of the wheel, a spring 180, fastened at one end to the pawl and encircling the hub of the wheel at its other end, serving to retain the nose 179 in such cutaway portion. Normally, the nose 179 of the pawl rides freely on the periphery of the supporting shaft 148, when the wheels are rotated by the actuating pawl 159 or 160 during an operation of the machine. The supporting shaft 148 is suitably supported for sliding movement in bearings in the side plates 32 and 33, and has mounted on its left-hand end (as viewed in Fig. 8) a collar 181, which prevents displacement of the shaft toward the right, and has mounted on its opposite end an operating handle 182, the inner end of the hub 184 of which is cored out to house a coiled spring 183 which is compressed between the side plate 32 and the end of the cored-out portion to normally retain the shaft 148 in the position shown in Fig. 8, in which position a notch 185 (Figs. 8 and 14) formed in a flange 186 on the inner end of the hub 184 engages the lower offset end of a stationary latch 187, fast on the plate 32, to prevent rotation of the crank 182 and hence of the shaft 148 when in normal position. When the counting wheels are to be turned to zero, the shaft 148 is slid toward the left by the handle 182 and against the tension of its spring 183, moving the notch 185 out of engagement with the latch 187, as shown in Fig. 9, and bringing shouldered recesses 188 in the shaft into the path of the noses 179 of the pawls 178, so that when the shaft is rocked counter-clockwise, as viewed in Fig. 6, by the handle 182, the shoulders of the recesses pick up the pawls 178 and restore the numeral wheels to zero. During this rotation of the handle 182 and shaft 148, the flange 186 is positioned between the plate 32 and the lower offset end of the latch 187 and thus the latch prevents the shaft and handle from being slid toward the right to normal position until at the end of a complete rotation of the handle, at which time the notch 185 is in alignment with the latch 187 and the numeral wheels have arrived at "0" positions.

Disabling multiplying attachment

When the Burroughs calculator is to be used in the usual manner by depressing the keys 27, without disturbing the mechanism of the multiplying attachment, a device is operated for disabling the multiplying at-

tachment, by locking the operating crank 56 against actuation and disconnecting the links or arms 42 from driving connection with the spring-pressed operating arms 45. This means constitutes a rock frame 191 (Fig. 16) formed of side plates 192 and 193 connected by three tie-bars 194, the side plate 193 having a shaft 195, (Figs. 16 and 17) supported in a bearing in the side plate 33, and the side plate 192 having a somewhat longer shaft 196 (Figs. 1, 4, 13, 16 and 17) supported in a suitable bearing in the side plate 32. Fast on the outer end of the shaft 196 is a hand lever or crank 197. The lower tie-bar 194 extends under the rear ends of all of the connecting arms or links 42, as best illustrated in Figs. 7 and 11, in which figures the rock frame 191 is shown in such position that the upper ends of the forward vertical portions of the bayonet slots 43 in the links 42 rest on the studs 44 on the operating arms 45, so that when the latter are operated the links and differential mechanisms are reciprocated, as above described. When the rock frame 191 is rocked 25 forwardly by its handle 197, to the position shown in Fig. 13, to disable the multiplying attachment it will be seen that the lower tie-bar 194 engages and raises the rear ends of the links 42 to move the vertical portions 30 of the bayonet slots 43 out of engagement with the studs 44 and that in this condition, the links 42 may be moved forwardly with the bell-crank levers B without disturbing the driving arms 45, when the keys 27 of the calculator are operated to operate the calculator in the usual way, the shouldered studs 44 then being clear of the forward vertical portions of the bayonet slots so that when the links are reciprocated their rear ends are supported by the studs 44 as the upper edges of the 40 horizontal portions of the slots then ride on the studs 44. When the frame 191 is rocked from its position shown in Fig. 13 to the position shown in Figs. 7 and 11, the intermediate cross rod 194 engages the upper edges of the links 42 and forces them downward to engage the forward vertical portions of their slots 43 with the studs 44, if the links do not fall to such position by gravity. The rollers 49 on the driving arms 47 (Fig. 7) are normally behind the projections 175 on the cam plates 50 so that with the multiplying attachment enabled, when the frame is in the position shown in Fig. 7, the keys 27 cannot be depressed because the links 42 are locked to the arms 45 and the arms 45 and 47 are locked against forward movement by the projections 175.

In order to lock the crank handle 56 and associated parts against operation, when the machine is to be operated under the control of the keys 27, the hub of the goose-neck cam plate 52 is provided, as best shown in Figs. 1 and 13, with a flanged collar 204, the flange of which is notched at 205 so that when the

frame 191 is rocked forwardly to disabling position, the nose of a pawl 206 fast on the shaft 196 engages the shoulder of the notch and hence blocks movement of cam plate and prevents operation of the operating crank 56. 70

The rock frame 191 is yieldingly retained in one or the other of its two positions of adjustment by a roller stud 198 mounted on the rear end of an arm 199 pivoted to the side frame 32, a spring 200 connected to the arm 199 serving to yieldingly retain the roller 198 in engagement with the upper edge of the side plate 192 of the frame. When the frame is in its rear position, in which position, as shown in Fig. 7, it permits the studs 44 to engage in the vertical portions of the slots 43, the roller 198 engages a curved depression or notch 201 on the plate 192 and when the frame is in its disabling position, shown in Fig. 13, the roller 198 is seated in a similar depression 202 to the rear of the depression 201, the frame being thus held in its position of adjustment against accidental displacement. 80 85

Means for locking machine against operation during zeroizing of counter 90

To prevent operation of the machine when the counter wheels 147 are being turned to zero, as above described, there is pivoted to the side plate 32 by screw stud 208 (Figs. 4 and 11) a bell-crank lever 209 whose upper end is bent in the direction of the side plate 32 to form a lug 210 (Figs. 4 and 14). The lower end of the lever 209 is provided with a slot 211 into which projects a pin 212, projecting inwardly from the downwardly extending end 217 of a goose-neck arm 213 fast to the right-hand end of a cross-shaft 214 journaled in brackets 215 which are secured to and extend forwardly from the side plates 32 and 33. A spring 216 connected at its opposite ends to the arm 213 and a stud on the calculator frame, acts to normally retain the end 217 of the arm 213 in engagement with the rear side of the roller stud 69 on the arm 66. When the arm 66 is rocked forwardly, during operation of the machine, by the operating cam plate 52, as above described, the spring 216 is permitted to rock the arm 213 forwardly, the end 217 following up the roller stud 69, and at the same time the pin 212 moves down in the slot 211 in the lever 209, as illustrated in Fig. 11, thus rocking the latter clockwise, as viewed from Figs. 4 and 11, to move its upper end with its lug 210 between the inner side of the flange 186 on the hub 184 of the zeroizing handle 182 and the side plate 32, the lug 210 being of sufficient width to block movement of the handle and shaft 148 toward the left, when between the hub flange and the plate. When the arm 66 is rocked rearwardly to normal position, shown in Fig. 4, the roller stud 69 being in engagement with the end 217 of the arm 213, moves the latter rearwardly and as its pin 120 125 130

212 moves upwardly in the slot 211 the lever 209 is rocked counterclockwise to normal position in which position its lug 210 is not between the flange 186 on the hub 184 and the side plate 32, thus permitting the shaft 148 and handle 182 to be shifted to the left so that when they are turned the shaft restores the counter wheels 147 to zero, as above explained.

10

Carriage locking mechanism

It is important that the shifting control carriage, comprising the slideway 75 and plate 76, be locked in any one of its columnar positions during operation of the operating crank 56 and to also lock the operating crank 56 against operation while the carriage is being shifted from one ordinal position to another, and to accomplish these ends the following mechanism is employed.

As best shown in Figs. 1, 4 and 5, there is fastened to the slideways 75 an angle plate 219, the horizontal flange 220 of which extends forwardly and is provided at its forward edge with notches 221 spaced apart a distance equal to that between two adjoining banks of keys 27. Fastened centrally on the shaft 214 is a vertical arm 222, which when the machine is in normal condition, is in alignment but out of engagement with, one of the notches 221, dependent upon the columnar position of the control carriage, so that the control carriage is free to be shifted to another ordinal position by the hand wheel 115. The goose-neck arm 213 (Fig. 4) fast on the right hand end of the shaft 214, carries a pin 223, projecting into a slot 224 formed in one arm of a bell-crank 225 pivoted on one of the screw studs 34. The rear free end of the other arm 40 of this lever is normally in front of a square block 226 secured to the inner side of the cam plate 52. During operation of the machine, when the arm 213 is rocked forwardly by the spring 216, as above described, the shaft 214 and arm 222 are rocked clockwise to the positions shown in Fig. 11, whereby the arm 222 is moved rearwardly into engagement with one of the notches 221, hence locking the control carriage against columnar shifting movement during operation of the operating crank 56. During this forward movement of the arm 213, the bell-crank lever 225, because of the pin-and-slot connections 223 and 224, is rocked to the position shown in Fig. 11 so that its rear end is moved out of the path of movement of the block 226 on the cam plate 52 to permit operation of crank 56, there being sufficient clearance normally between the rear end of the lever 225 and block 226 to permit 55 the end of the lever to be moved away from in front of the block during the first increment of movement of operation of the cam plate 52 by the crank 56. During shifting movement of the control carriage from one 60 ordinal position to another, the notches 221

are out of alignment with the arm 222 so that, should an attempt be made at such time to operate the operating crank 56, the forward edge of the flange 220 between the notches would block movement of the arm 222 and hence prevent movement from normal position of the arm 213 and the bell-crank 225 by the spring 216 and, as the lever 225 would thus be held in its normal position, its rear end, being in front of the lug or block 226, would block movement of the cam plate 52 and hence of the operating crank 56.

It is also desirable to prevent operation of the machine while the finger piece 126 and associated levers 123 and 128 are being moved from one position to another, during which time the carriage plate 76 is shifted relative to the slideway 75 to condition the machine for subtraction (division) or addition (multiplication), as the case may be. To this end the lower end of the lever 123 is provided with an extension 230 (Figs. 1 and 5) projecting into a notch 231 in a slide-plate 232 mounted for sliding movement on the flange 220 by means of screw studs 233 threaded into the flange 220 and projecting through slots 234 in the plate 232. This plate 232 has six pairs of notches 235 in its front edge, so spaced that the right-hand (as viewed in Fig. 1) notches of the pairs register with the notches 221 in the flange 220 when the carriage control plate 76 is set for addition, and the left-hand notches of the pairs register with the notches 221 when the control carriage plate 76 is set for subtraction, the plate 232 being shifted from one position to the other by the lever 123, when the machine is conditioned accordingly for addition or subtraction by the finger-piece 126. During the time the carriage plate 76 is being shifted from adding to subtracting position, or vice versa, the projections of the plate 232 between the notches of the pairs are in alignment with the notches 221 in the flange 220 and their outer ends form abutments which prevent entrance of the locking arm 222 into the notches 221 until the carriage plate 76 has traveled its full movement to either subtractive or additive condition.

Shiftable pointers for accumulator wheels and counter wheels

In order to indicate the number of decimal places in the dividend set upon the accumulating wheels A, there is provided the usual track 238 with a slidable pointer 239 mounted thereon, as shown in Fig. 1. A similar pointer 240 is mounted to slide on a track 241 positioned on the cover 150 and above the sight-openings therein for the purpose of pointing off the proper number of decimal places in the quotient as will be described presently more fully in connection with the description of the operation of the machine in performing a problem in division.

Operation

The operation of the machine in view of the above detailed description is thought to be obvious, but to recapitulate, the operation of the machine will be explained in a more or less general way in connection with the performance of concrete examples or problems in multiplication and division.

- Let it be assumed that 455 is to be multiplied by 54. The control carriage is shifted to the extreme right—to its first or units position—by the hand wheel 115, if the carriage is not already in that position, and the machine is conditioned for multiplication by moving the finger-piece 126 to the "A" (add) position as shown in Fig. 1, if it is not already in such position. The hand crank W is operated to clear the accumulator wheels A and the hand crank 182 is shifted toward the left and then given one rotation to turn the counter-wheels 147 to zero position, if these wheels have not been set to "0" at the end of the preceding calculation. The three finger-pieces 78 on the hundreds, tens and units indexing stop units are then moved until the corresponding indicating wheels 88 display the number "455" through the sight openings 87, while the indexing stop units of higher order are set to their "0" positions.
- The operating crank 56 is now given four strokes or rotations, as the digit "4" appears in the units order in the multiplier. During each stroke of the crank 56, the units and tens operating arms 45 are arrested at the end of their fifth step of movement by engagement with their lugs 97 against the "5" stops on the adding plates 81 on the units and tens control units, and the driving arm 45 for the hundreds order is arrested by engagement of its lug 97 with the "4" stop on the hundreds adding plate 81, while the driving arms 45 of the next three higher denominations are held in zero position by the "0" stops on the corresponding adding plates, the arms 45 of still higher denominations being also arrested in "0" position by the auxiliary stop arms 100. Movement of the units and tens driving arms 45 five steps and movement of the hundreds arms four steps actuate the actuating devices for the corresponding accumulator wheels A accordingly, to add "455" on these wheels during each stroke of the operating crank 56. It will be remembered that during a multiplying operation actuation of the arms 45 in all orders higher than those set up by the indexing fingers 78 is prevented by the upper ends of the arms 45 engaging the cipher stops on the adding indexing plates 81 and to the left of the adding indexing plates by the stops 100. Also, upon each stroke of the operating crank 56 the lever 170 is rocked by the cam 50 appropriate to the units order and the roller 167 on the lever 170 rocks the units pawl-carrying

arm 158 and at the same time disables the quotient pawl 160 (as shown in Fig. 11) so that the multiplier pawl rotates the units counter wheel 147 one step counterclockwise to add "1" thereon and at the end of the fourth stroke of the operating crank, the digit "4" of the multiplier series of digits on the units wheel 147 is displayed through the sight-opening 149 and 152, the plate 151 having been moved to "A" (add) position by the finger-piece 154 when the machine was conditioned for performing the problem.

The control carriage is now shifted one order toward the left by turning the hand wheel 115, thereby transposing or trans-setting the multiplicand "455" one order or place to the left so that the first or units adding plate 81 is now in operative alignment with the driving arm 45 of the tens order. During this movement of the carriage, the right-hand end of the bail 104 moves out of engagement with the nose 103 on the latch 101 for the units order and the spring 107 rocks this latch to move its nose 105 in front of the lug 106 on the units driving arm 45 to lock this arm against actuation. The operating crank 56 is now given five strokes, as "5" appears in the tens denomination of the multiplier, and during each stroke the hundreds and tens actuating devices for the accumulator are given five extents of movement, being controlled by the "5" stops on the adding plates 81 of units and tens orders on the control carriage and the thousands actuating device is given four extents of movement, the thousands driving arm 45 being arrested by the "4" stop of the third or hundreds adding plate 81, "4550" hence being added on the accumulator during each stroke of the crank. When the carriage is shifted to its tens position, the lever 170 is moved to operative alignment with the tens pawl-carrying arm 158 so that upon each stroke of the crank 56 the tens counting wheel 147 is moved one step so that at the end of the fifth stroke the counter displays the number "54", which is the multiplier. At the same time the product shown on the accumulating wheel is "24570", which is the product of 455 multiplied by 54.

Assume, now, that the machine is to be used for performing a division calculation and that 2390.58 is to be divided by 540. The accumulator and counter are both turned to zero, the finger-piece 126 is moved to its "S" (dividing) position and the sight slide 151 is likewise moved to its "S" (dividing) position by the finger-piece 154 so that its sight-openings 152 are moved into alignment with the shaded series of digits on the counting wheels 147, which are to show the quotient. Movement of the finger-piece 126 through the shifting lever 128 moves the carriage plate 76 relative to the slideway 75, to move the adding plates 81 out of operative align-

ment with the driving arms 45 and to move the subtracting plates 82 into such alignment, the arms 100, which are the stop arms for the higher denominations, being likewise moved 5 out of the zones of the movement of the driving arms 45. The crank 197 is rocked forwardly to move the frame 191 so that its lower cross-rod 194 raises the rear ends of the links 42 to break their driving connections 10 with the driving arms 45, as shown in Fig. 13, and hence permit operation of the calculator keys 27 to set up the dividend on the accumulating wheels A. As the dividend, set up on the accumulator, has two decimal places 15 the pointer 239 is moved to its position between the second and third accumulator wheels to indicate the place of the decimal point. The crank 197 is then moved rearwardly so that the links 42 are lowered into 20 driving connection with the operating arms 45 as shown in Figs. 7 and 12. As "0's" to the right of the valued digit of lowest order in the divisor are disregarded in setting up the divisor on the control carriage, the present divisor "540" is set up as "54" by moving the 25 first or units finger-piece 78 and indexing stop unit to their "4" position and the second or tens finger-piece 78 and indexing stop unit to their "5" position, the units and tens 30 indicating wheels 88 being turned thereby to display the partial divisor "54". It is understood that the finger-pieces 78 of the higher orders are moved to their "0" positions, if they are not already in such positions. The 35 control carriage is now shifted to its fourth columnar position by the hand wheel 115, after the operator has observed that the partial divisor "54" is not contained in that portion of the dividend represented by the two 40 digits—"23"—of highest orders and that it will be contained in the three highest digits—"239"—of the dividend. The operator now operates the crank 56 and at or near the end of each rotation thereof, notes the remainder on the accumulator wheels of higher orders than the hundreds wheels, to see if the divisor is contained in each successive remainder. During each of these strokes of the 45 operating handle 56, the lugs 97 of the thousands and tens of thousands operating arms 45 engage the "6" and "4" stops on the first "units" and second (tens) subtracting plates 82, respectively, these arms being moved forwardly extents corresponding to the values 50 of the respective engaged stops, or, in other words, the thousands arm is moved forwardly six steps, which is the complement of "4" with respect to "10", and the tens of thousands arm 45 is moved forwardly four steps, which 55 is the complement of "5" with respect to "9", it being remembered that the operating arm 45 controlled by the units subtraction plate is being moved an additional step for the purpose of adding the extra "1" on the accumulating wheel A in alignment therewith 60

to complete the full complement of the divisor, as is well understood in the art. The arms 45 of higher denominations are moved nine steps to add "9s" on the accumulator wheels of corresponding denominations and the arms 45 of three lowest denominations are latched against movement by the corresponding latches 101 which were rocked to their latching positions as the bail 104 was moved out of engagement with their noses 103 when the control carriage was shifted to its fourth columnar position. 70 75

At the end of the fourth stroke of the operating crank, with the control carriage in its fourth position, the operator will note that the partial divisor, "54" is not contained in the partial remainder displayed on the thousands and tens of thousands accumulator wheels A, this remainder now being "23", so he shifts the control carriage one step to the right to its hundreds or third position. During each of the strokes of the crank 56, while the carriage is in its fourth position, the lever 170 is oscillated and upon each oscillation its roller 167 engages the thousands pawl-carrying arm 158 and the tail 164 of the multiplier pawl 159, to disable it, and as the roller 167 is out of engagement with the quotient pawl 160, being so conditioned by the shifting of the control carriage to subtracting condition, the 80 quotient pawl 160 upon forward movement of the arm 158 engages the ratchet 157, as shown in Fig. 12, and moves the thousands counting wheel 147 one step clockwise to add "1" thereon, so that at the end of the fourth stroke, 85 the digit "4", of the quotient series of digits, is displayed through the corresponding sight openings 149 and 152. 90 95 100

With the control carriage in its third position, the operating crank 56 is given four strokes and at the end of the fourth stroke the operator will note that the partial remainder "14" on the hundreds and thousands accumulating wheels A does not contain the partial divisor "54" so he shifts the control carriage one step further toward the right to its second or tens position. When the control carriage was shifted to its third position, the bail 104 picked up the latch 101 for the hundreds arm 45, to permit this arm to be moved "6" steps 105 under the control of the first or units subtracting plate 82 during each stroke of the crank 56 with the control carriage in its third position. While the carriage was in its third position the hundreds counting wheel 147 110 was given four steps of movement by the lever 170, in the same manner as the thousands wheel 147 was operated with the control carriage in its fourth position. 115 120

With the control carriage in its second position, the operator turns the operating crank 56 twice and at the end of the second stroke notes that the partial remainder "37" on the tens and hundreds accumulator wheels A does not contain the partial divisor "54", so he 125 130

moves the carriage to its extreme right-hand or units position. While the control carriage is in its second position "2" is added on the tens counting wheel 147, the handle crank 56 having been given two strokes.

With the control carriage in its first or units position, the operator gives the operating crank 56 seven strokes, as "54" is contained in the remainder, "378", exactly seven times, which clears the accumulator. At the same time "7" is displayed by the units counting wheel 147, the whole quotient displayed being "4427".

Now, as the correct divisor is "540", and the "0" was disregarded in setting up the divisor on the control carriage, and as there are two decimal places in the dividend, as indicated by the pointer 239, and the rule for locating the pointer 240 is to move this pointer to point off as many places as there are ciphers in denominations to the right of the valued digit of lowest order in the divisor plus the number of decimal places in the dividend, the pointer 240 in the present example is moved three places to the left (from its extreme right-hand position) and consequently our correct quotient in the above example is "4.427".

It will now be seen that the above described constructions are well calculated to accomplish the objects, primarily stated. At the same time it is to be understood that these constructions are susceptible of considerable modification without departure from the scope and spirit of the invention and consequently in the claims which follow the essential elements are recited without limitation to details of construction.

I claim:

1. In a machine of the class described, the combination of an accumulator, actuators therefor, means connected to the actuators for driving them, sets of complementally arranged differential stops for arresting movement of said driving means, means for selectively moving said sets of stops to active position, and means for moving the stops of the selected set to differential positions.

2. In a machine of the class described, the combination of an accumulator, an actuator therefor, a driving arm connected to said actuator, a driving means yieldingly connected to said driving arm and having an invariable extent of movement, a pair of complementally arranged differential stops for arresting movement of the driving arm, means for moving said stops to differential positions, and means for selectively moving said stops to position to arrest said driving arm.

3. In a machine of the class described, the combination of an accumulator, an actuator therefor, means connected to said actuator for driving it, a laterally movable slide, a pair of vertically movable complementally stepped plates on said slide for arresting said

driving means in differential positions, means for moving said plates vertically to differentially position them, and means for moving said slide laterally to selectively move the stepped plates to position to arrest the driving means.

4. In a machine of the class described, the combination of an accumulator, an actuator therefor, a driving arm connected to the actuator, a driving means yieldingly connected to the driving arm and having an invariable extent of movement, a laterally movable slide, a pair of vertically movable complementally stepped plates on said slide for arresting said driving means, means for moving said slide laterally to selectively move said stepped plates to position to arrest movement of the driving arm, and means for moving said plates vertically to differentially position them.

5. In a machine of the class described having depressible amount keys, and differentially movable actuators; the combination of differentially settable control units comprising complementally arranged adding and subtracting stops for limiting the extent of movement of said actuators independently of said keys, means for differentially setting said control units, means for selecting the adding or subtracting stops for effective control of said actuators, and means for moving the actuators to differential positions.

6. In a machine of the class described having depressible amount keys and differentially movable actuators; the combination of differentially settable control units each comprising a pair of complementally stepped adding and subtracting plates, means for driving said actuators solely under the control of said adding or subtracting plates, and means for selecting the adding or subtracting plates for effective control of said actuators.

7. In a machine of the class described having depressible amount keys and differentially movable actuators; an operating means for driving said actuators through yielding connections independently of said keys, control units each comprising a pair of complementally stepped adding and subtracting plates, the adding and subtracting plates respectively being adapted to arrest said actuating devices in positions proportional and complemental to the setting of said control units, manual means for differentially positioning said control units, and means for selecting the adding or subtracting plates for effective control of said actuating devices.

8. In a machine of the class described, the combination of an accumulator, differential actuating devices therefor, a keyboard comprising amount-determining manipulative devices for controlling the extents of movement of said actuating devices when the determining devices are employed, an operating mechanism for actuating said actuating

- devices, control units, each comprising a pair of complementally arranged adding and subtracting elements adapted, respectively, to arrest movement of said actuating devices 5 in positions proportional and complemental to the setting of said control units, means for selecting the adding or subtracting elements for effective control of said actuating devices, means for preventing control of said actuating devices by said amount-determining manipulative devices when said actuating devices are to be driven by said operating mechanism, and means for locking said operating mechanism against operation when 15 said actuating devices are to be controlled by said amount-determining manipulative devices.
9. In a machine of the class described, the combination of an accumulator, differential actuating devices therefor, a keyboard comprising amount-determining manipulative devices for driving said actuating devices, an operating mechanism for driving said actuating devices, means connecting said actuating devices to said operating mechanism, means controlling the extents of movement of said actuating devices when driven by said operating mechanism, means for disconnecting said actuating devices from said operating mechanism when the actuating devices are to be driven by said amount-determining manipulative devices, and means for preventing actuation of said actuating devices by said amount-determining manipulative devices when said operating mechanism is connected to said actuating devices. 25
- 30 10. In a machine of the class described, the combination of an accumulator, differential actuating devices therefor, a keyboard comprising amount-determining manipulative devices for driving said actuating devices, an operating mechanism for driving said actuating devices, means connecting said actuating devices to said operating mechanism, amount-determining means, manipulatively controlled, for controlling the extents of movement of said actuating devices when driven by said operating mechanism, and means for disconnecting said operating mechanism from said actuating devices and locking said operating mechanism against operation when said disconnection is effected and for preventing actuation of said actuating devices by said amount-determining manipulative devices of said keyboard when the operating mechanism is connected to said actuating devices. 35
- 40 11. In a machine of the class described, the combination of an accumulator, differential actuating devices therefor, a keyboard comprising amount-determining manipulative devices for controlling the extents of movement of said actuating devices, an operating mechanism including spring-operated arms, means connecting said actuating de-
- vices to said arms, manually controlled means for controlling the extents of movement of said arms and actuating devices when driven by said operating mechanism, and means for disabling said connecting means when said actuating devices are to be driven under the control of the amount-determining devices of said keyboard. 45
- 50 12. In a machine of the class described, the combination of an accumulator, of differential actuating devices therefor, a keyboard comprising amount-determining manipulative devices for controlling the extents of movement of said actuating devices, an operating mechanism including spring-operated arms, links connecting said actuating devices to said arms by engagement of a recess in one with a pin on the other, manually controlled means for controlling the extents of movement of said arms and actuating devices when driven by said operating mechanism, and means for disengaging said recesses from said pins when said actuating devices are to be actuated under the control of said amount-determining manipulative devices. 55
- 60 13. In a machine of the class described, the combination of an accumulator, differential actuating devices therefor, a keyboard comprising amount-determining manipulative devices for controlling the extents of movement of said actuating devices, an operating mechanism including spring-operated arms, links connecting said actuating devices to said arms by engagement of a recess in one with a pin on the other, manually set control units comprising complementally arranged elements for controlling the extents of movement of said arms and actuating devices when driven by said operating mechanism, and means for disengaging said notches from said pins when said actuating devices are to be actuated under the control of said amount-determining manipulative devices and for locking said operating mechanism against operation. 65
- 70 14. In a machine of the class described, the combination of an accumulator, differential actuating devices therefor, a keyboard comprising amount-determining manipulative devices for controlling the extents of movement of said actuating devices, an operating mechanism including spring-operated arms, links connecting said actuating devices to said arms by engagement of a recess in one with a pin on the other, manually controlled means for controlling the extents of movement of said arms and actuating devices when driven by said operating mechanism, and a manually operated rock frame having a bar for raising said links to disengage said recesses from said pins. 75
- 80 15. In a machine of the class described, the combination of an accounting mechanism, actuators therefor, an ordinally shiftable carriage, devices on said carriage for con-

- trolling the extent of movement of said actuators, the lower orders of said devices moving out of position to control said actuators as the carriage is shifted, and means for automatically locking the respective actuators of lower order against operation as the devices on the carriage move out of controlling position relative to said lower-order actuators during the shifting of the carriage.
16. In a machine of the class described, the combination of an accumulator, actuators therefor, an ordinarily shiftable carriage, devices on the carriage for controlling the extents of movement of said actuators in operative relationship therewith, latches for latching the actuators of lower denominations out of operative relationship with said devices, against actuation, and means on the carriage for controlling said latches.
17. In a machine of the class described, the combination of an accounting mechanism, actuating devices therefor, an ordinarily shiftable carriage, differentially set control units on the carriage for controlling the extents of movement of said actuating devices, latches associated with the actuating devices of lower orders for latching these actuating devices against actuation when the control units are out of operative relationship with the same, and a member fixed on said carriage for successively disabling said latches as the carriage is shifted to move the control units into operative relation with their actuating devices.
18. In a machine of the class described, the combination of an accounting mechanism, of actuators therefor, operating mechanism, arms associated with the actuators and yieldingly driven by said operating mechanism, an ordinarily shiftable carriage, control devices for the carriage for controlling the extents of movement of said arms and actuators and adapted to be shifted successively into and out of controlling relation with certain of said arms, latches for said last-mentioned arms to prevent actuation of the latter, and means for successively enabling and disabling said latches as said control devices are moved successively out of and into operative relation with their appropriate arms.
19. In a machine of the class described, the combination of an accounting mechanism, of actuators therefor, operating mechanism, arms associated with said actuators and yieldingly driven by said operating mechanism, an ordinarily shiftable carriage, control devices on the carriage for controlling the extents of movement of said arms and actuators and adapted to be shifted successively into and out of controlling relation with certain of said arms, latches for said last-mentioned arms to prevent movement of the latter, and a bail having a cam portion for cooperating with said latches to successively enable and disable said latches as said control devices are moved successively out of and into operative relationship with the appropriate arms.
20. In a machine of the class described, the combination of an accumulator, actuators therefor, an ordinarily shiftable carriage, devices on the carriage for controlling the extents of movement of said actuators in operative relationship therewith, latches for latching the actuators of lower orders against operation when these actuators are out of operative relationship with said devices, and a bar on said carriage having one end inclined to successively engage projections on the latches to move the same out of latching condition as the carriage is shifted ordinarily from higher to lower orders.
21. In a machine of the class described, the combination of an accounting mechanism, actuating devices therefor, an ordinarily shiftable carriage, control units on the carriage, each comprising complementally arranged adding and subtracting elements for arresting differential movement of the actuating devices in multiplying and dividing operations, respectively, latches for the actuating devices of lower orders for latching these actuating devices against actuation when the control units are out of controlling relation therewith in multiplying and dividing operations, means for successively disabling said latches as the carriage is shifted to the columnar positions appropriate to the denominations of the latches in dividing operations and permitting the latches successively to move to latching position as the carriage is shifted out of columnar positions appropriate to the denominations of the latches in multiplying operations.
22. In a machine of the class described, the combination of an accounting mechanism, actuating devices therefor, an ordinarily shiftable carriage, control units on the carriage, each comprising complementally arranged adding and subtracting elements for arresting differential movement of said actuating devices in multiplying and dividing operations, respectively, latches for the actuating devices of lower orders for latching these actuating devices against actuation when the control units are out of controlling relationship therewith in multiplying and dividing operations, springs for successively moving the latches into latching position during a multiplying calculation, and a bar having an inclined portion for cooperating with the projections on the latches for successively disabling the latter during a dividing calculation.
23. In a machine of the class described, the combination of an accumulator, actuating means therefor, a stationary track, a carriage ordinarily shiftable on said track said carriage having a slide member on the track and a control plate mounted on said member for movement relative thereto, devices on said

- plate for controlling movement of said actuating means during additive and subtractive operations, means for moving said control plate relative to said supporting slide 5 member to condition said devices for addition or subtraction, and means for ordinarily shifting said carriage.
24. In a machine of the class described, the combination of a counter comprising numeral wheels having two series of reversely arranged digits, a movable member associated with each wheel, a pair of actuating pawls on each member adapted to rotate the wheels in opposite directions, and means for selectively operating said members and disengaging one or the other of said pawls to permit actuation of the selected counter wheel by the other pawl of the pair.
25. In a machine of the class described, the combination of a counter comprising numeral wheels having two series of reversely arranged digits, a movable member associated with each wheel, a pair of actuating pawls on each member adapted to rotate the wheels in opposite directions, an ordinarily shiftable carriage, and means for selectively operating the member appropriate to the ordinal position of the carriage and disabling one of the pawls thereon.
26. In a machine of the class described, the combination of a counter comprising numeral wheels, each having two series of reversely arranged digits, a movable member associated with each wheel, a pair of actuating pawls on each member, adapted to rotate the wheels in opposite directions, a carriage adapted to be shifted from order to order and to be shifted from one control position to another, an element shifted with said carriage for selectively actuating the member appropriate to the ordinal position of the carriage and causing the pawl on said member and appropriate to the control condition of the carriage to actuate the corresponding counter wheel.
27. In a machine of the class described, the combination of a counter comprising numeral wheels each having two series of reversely arranged digits, a movable member associated with each wheel, a pair of actuating pawls on each member adapted to rotate the wheels in opposite directions, a carriage adapted to be shifted ordinarily and to be shifted from one control condition to another, and an element on said carriage for actuating the movable member appropriate to the ordinal position of the carriage and disabling one of the pawls to permit the other pawl thereon to rotate its wheel in the direction appropriate to the control condition of the carriage.
28. In a machine of the class described, the combination of an accumulator, actuators therefor, a shiftable carriage, control units on the carriage for controlling actua-
- tion of the actuators in multiplying and dividing operations, means for shifting said carriage from order to order, means for shifting said carriage to condition the control units for multiplication or division, a counter comprising numeral wheels, multiplier and quotient pawls for each wheel, and a member on said carriage for effectively operating the pawl appropriate to the control condition of the carriage and to the ordinal position of the carriage.
29. In a machine of the class described, the combination of an accumulator, actuating devices therefor, a driving device for each actuating device, a shiftable carriage, control units on the carriage for controlling actuation of the actuating devices in multiplying and dividing operations, means for shifting said carriage from order to order, means for shifting said carriage to condition the units for multiplication or division, a counter comprising numeral wheels, multiplier and quotient pawls for each wheel, and a member on said carriage for effectively operating the pawl appropriate to the ordinal position of the carriage and to the control condition of the carriage, said member being operated by the driving device appropriate to the ordinal position of the carriage.
30. In a machine of the class described, the combination of a counter comprising numeral wheels having two series of reversely arranged digits, a shaft supporting the wheels, an arm for each wheel pivoted on said shaft, a pair of pawls on each arm adapted to rotate the numeral wheels in opposite directions, a carriage adapted to be shifted ordinarily and to be shifted from one control condition to another, an element on said carriage movable into operative relation with the arm appropriate to the ordinal position of the carriage, and means for operating said element to rock the arm in operative relation therewith and engage and disengage the pawl thereon which is not appropriate to the particular control condition of the carriage.
31. In a machine of the class described, the combination with an accumulator, actuating devices therefor, an ordinarily shiftable carriage, control units each comprising complementary arranged adding and subtracting plates, adapted to arrest the actuating devices in positions proportional to or complementary to, respectively, the setting of the control units, fixed devices on the carriage for arresting the actuating devices of higher orders in zero positions when the control units are out of operative relation with the same and the actuating devices of lower orders are moved to extents proportional to the setting of the control units, means for differentially positioning said control units, and means for shifting the control units to select the adding or subtracting plates for

effective control of the actuating devices and for also shifting said fixed devices to move the same out of operative relation with the actuating devices of higher orders when the same are out of operative alignment with the control units and the actuating devices of lower orders are moved extents complementary to the setting of the control units.

32. In a machine of the class described, the combination of an accumulator, actuators therefor, operating mechanism for driving said actuators, a control carriage, adding and subtracting devices thereon for arresting said actuators, means for shifting said carriage

10 to condition said devices for addition or subtraction, and interlocking means comprising a slide on the carriage having notches and an arm operated by the operating mechanism and adapted to cooperate with said notches 15 to prevent such shifting movement of the carriage during operation of the operating mechanism and prevent operation of the operating mechanism during such shifting movement of the carriage.

33. In a machine of the class described, the combination of an accumulator, differential actuators therefor, operating mechanism for driving said actuators, an ordinarily shiftable carriage, control units thereon comprising adding and subtracting devices for arresting said actuators, means for ordinarily shifting said carriage, means for shifting said carriage to condition said devices for addition or subtraction, and means for preventing operation of said operating mechanism when said carriage is being ordinarily shifted or being shifted to condition said devices and for preventing either of said shifting movements of said carriage during operation of 40 the operating mechanism.

34. In a machine of the class described, the combination of an accumulator, actuators therefor, operating mechanism for driving said actuators, an ordinarily shiftable carriage, control units thereon comprising adding and subtracting devices for arresting said actuators, means for ordinarily shifting said carriage, means for shifting said carriage to condition said adding and subtracting devices for addition or subtraction, and an interlocking means comprising a plate on the carriage, a slide on the plate and an arm operated by the operating mechanism and adapted to cooperate with notches in said plate and slide, whereby the operating mechanism is locked against operation when the carriage is shifted ordinarily or to condition said adding and subtracting devices and the carriage is locked against either of the shifting movements during operation of the operating mechanism.

35. In a machine of the class described, the combination of an accumulator, actuators therefor, operating mechanism for driving said actuators, an ordinarily shiftable car-

riage, comprising a supporting member and a control member mounted for sliding movement on the supporting member, adding and subtracting devices on said control member for arresting said actuators, means for shifting said control member on said supporting member of the carriage to condition said adding or subtracting devices for addition or subtraction, and means actuated by said moving means for preventing operation of the operating mechanism during movement of said moving means to condition said devices.

36. In a machine of the class described, the combination of an accumulator, actuators therefor, operating mechanism for driving said actuators, an ordinarily shiftable carriage, comprising a supporting member and a control member mounted for sliding movement on the supporting member, adding and subtracting devices on said control member for arresting said actuators, means for shifting said control member on said supporting member of the carriage to condition said adding or subtracting devices for addition or subtraction, means actuated by said moving means for preventing operation of the operating mechanism during movement of said moving means to condition said devices, and means operated by the operating mechanism for preventing shifting movement of the carriage during operation of the operating mechanism.

37. The combination in a calculating machine of manipulative amount determining devices each of which includes two sets of complementally arranged stops positioned by said devices, an accumulator, actuators for said accumulator, each actuator having a member associated therewith for engaging the stops for its actuator whereby movement of the actuator is limited, means connected to the actuators for moving them, and means for selectively determining which set of stops shall be engaged by said members.

38. The combination with a key driven calculator having an accumulator, and actuators therefor, of an attachment adapted to be connected to the rear of the machine comprising a driving means, connections for connecting the driving means to the actuators independently of the amount keys, differential stops for arresting the driving means in differential positions, and means for moving said differential stops to differential positions.

39. The combination with a key driven calculator having a counter, and actuators therefor; of an attachment adapted to be connected to the rear of said machine comprising driving arms, a crank operated driving means for yieldingly moving said driving arms, means for connecting said driving arms to the actuators independently of the amount keys, differential stops for limiting the move-

ment of the driving arms, and means for setting said stops in differential positions.

40. The combination with a key driven calculator having an accumulator, and actuators therefor; of an attachment adapted to be connected to the rear of the machine comprising driving arms, a crank operated driving means yieldingly connected to said arms, means for connecting said arms to the actuators independently of the amount keys, a set of differential stops for limiting the movement of the driving arms, a second set of differential stops complementally arranged relative to the first for limiting movement of the driving arm, means for setting said stops in differential positions, and means for selectively moving the sets of stops to position for limiting the movement of the driving arms.
